UNITED STATES PATENT OFFICE.

SAMUEL STRASBURGER, OF BOSTON, MASSACHUSETTS,

DESIGN FOR WATCH-CASES.

Specification forming part of Design No. 7,774, dated September 22, 1874; application filed April 23, 1874.
[Term of Patent 7 years.]

CASE C.

To all whom it may concern:

Be it known that I, SAMUEL STRASBURGER, of Boston, in the county of Suffolk and State of Massachusetts, have invented a Design for Ornamenting Watch-Cases, of which the following is a specification:

Figure 1 is a front view, the reverse side being the same; and Fig. 2, an edge view of my ornamental watch-case.

Like letters indicate corresponding parts in the different figures of the drawing.

My invention relates more especially to what are known as flat cases which have beveled or angular edges; and consists of a novel ornamentation of the parts, as hereinafter more fully set forth and claimed, by which a new and very beautiful effect is produced.

In Fig. 1, D is the top of the case or central portion of the lid, which is surrounded by the plain band C. A plain beveled edge, B, extends from the plain band C down to the border A of the lid, which is ornamented with a series of fine double lines arranged in parallelism, being crossed by other similar lines diagonally, so as to divide this part of the case into diamond or lozenge shaped spaces, as shown in Fig. 2, the entire border and the edge E being thus ornamented. The part D

of the lid is ornamented with lathe-work, or is engine-turned, and has a central figure, consisting of a basket of fruit and flowers, with a "lovers' knot" tied in a ribbon attached to the handle of the same.

I use lathe-work for ornamenting the part D, and prefer the use of lines for ornamenting the border A and edge E, as shown; but other styles of ornamentation may be substituted for the border and edge without departing from the spirit of my invention, the distinctive character of which is an ornamental border, A, and edge E, so combined with the ornamental part D as to leave the plain ring C and plain beveled edge B between the two.

What I claim as my invention is—

A design for a watch-case, consisting of the central lathe-work D, surrounding plain-surfaced ring C, and beveled edge B, and outside edge E, and border A, of parallel lines crossing each other diagonally, as described.

In testimony whereof I have hereunto subscribed my name this 20th day of April, 1874.

SAMUEL STRASBURGER.
